CLAIM

The ornamental design for an infant walker as shown and described.

DESCRIPTION

FIG. 1 is a perspective view of an infant walker showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The evenly-dashed broken lines shown in the drawings depict portions of an infant walker which form no part of the claimed design.

The dot-dash broken lines in FIG. 3 are for defining the bounds of the claimed design only and form no part of the claimed design.
